United States Patent Office

Des. 198,057
Patented Apr. 21, 1964

198,057

FOOD STORAGE CONTAINER

James B. Swett, Barrington, R.I., assignor to Rexall Drug and Chemical Company, Los Angeles, Calif., a corporation of Delaware

Filed July 7, 1961, Ser. No. 65,840

Term of patent 14 years

(Cl. D58—17)

FIG. 1.

FIG. 2.

FIG. 3.

FIG. 4.

FIG. 1 is a view in perspective of a food storage container showing my new design;

FIG. 2 is a top plan view thereof;

FIG. 3 is a side elevation thereof;

FIG. 4 is an end view thereof.

I claim:

The ornamental design for a food storage container, as shown.
